UNITED STATES PATENT OFFICE.

CHARLES F. SCHULTIS, OF CLEVELAND, OHIO, ASSIGNOR OF ONE-HALF TO WILLIAM J. SCHOENBERGER, OF CLEVELAND, OHIO.

PRESS FOR SQUEEZING SAND IN FLASKS.

1,400,321.

Specification of Letters Patent.

Patented Dec. 13, 1921.

Application filed July 2, 1920. Serial No. 393,492.

To all whom it may concern:

Be it known that I, CHARLES F. SCHULTIS, a citizen of the United States, residing at Cleveland, in the county of Cuyahoga and State of Ohio, have invented certain new and useful Improvements in a Press for Squeezing Sand in Flasks, of which the following is a specification.

This invention relates to an improvement 10 in a press, and more particularly in a press of the type used for pressing or squeezing sand in flasks preliminary to removing the patterns for casting operations, and it is especially designed to effect pressing or squeezing of the sand either by hand or power as the operator of the machine may elect or the conditions at the time of use may require. Compressed air is used as the power medium and the application of power by hand is 20 through a lever, and if the use of compressed air is dispensed with for any considerable period of time the operator may readily disconnect the power parts and avoid the labor of actuating said parts while operating the 25 machine through the medium of the hand lever. The squeezing plate is adjustably mounted on a swinging arm which is in turn adjustably supported upon a vertical post, and the table which is used to support 30 the mold or flask is movable vertically within limits to effect the pressing or squeezing of the sand by movement of the table and mold upwardly toward the squeezing plate.

In the drawing accompanying this application, Figure 1 is a side view of the complete machine with the table lowered and ready to receive a flask. Fig. 2 is a front view of Fig. 1. Fig. 3 is a horizontal section on line 3—3, Fig. 1, excepting the cylinder which is shown in plan. Fig. 4 is a plan view of the machine. Fig. 5 is a central vertical section of the machine, showing the piston disconnected and the table elevated by the hand lever. Fig. 6 is a side view and 45 section showing the piston connected and in a forward position with the table elevated.

The machine comprises a base plate 2 to which a pair of I-beams 3 are bolted in parallel upright position, and a round post 4 50 extends above said beams and has a rectangular portion 5 seated between the flanges thereof and bolted rigidly thereto. The base plate 2 and lower portion of the beams may be embedded in a cement floor, or these parts 55 may be supported in an upright position in

any practical way, but as constructed and set up these parts provide a very simple, strong and cheap support for a vertically movable table 6, a horizontally-reciprocable piston 7, and a swinging arm 8 for a presser 60 plate 9 which is adapted to be placed centrally above the table.

Piston 7 is confined within a cylinder 10 having a stuffing box 11 at one end where bolted to the rear side of I-beams 3, and the 65 piston rod 12 has an open hook 13 screwed within its end and the rod is adapted to reciprocate horizontally between and parallel to the sides of the two I-beams. Piston 7 is double acting, that is, it is adapted to be operated in opposite directions when compressed air is passed alternately into the opposite ends of the cylinder through pipes 14 and 15 and which connect with a 3-way or other suitable valve 16 within convenient 70 reach of the operator. As shown, valve 16 is supported by a bracket 17 at the front of a cast-iron saddle 18 which is bolted in a straddling position to the front side of the I-beams 3 directly opposite cylinder 10. Table 6 is supported by a vertical stem 19 which is slidably mounted in bearings 20' of saddle 18, and separate pairs of toggle links 20—20 are pivotally supported on pivot pins 21 fixed to the sides of the saddle and 80 to a pivot pin or pins 22 extending through the hub of the table. When these toggle links are caused to straighten the table is 85 forced upward, and this action may be brought about by the movement of the piston 90 and a link 23 which is adapted to connect with the toggle pin 34. Thus, link 23 is in the form of a yoke and has a cross pin 35 adapted to be detachably engaged with the hook 13 of piston rod 12, see Figs. 3 and 95 6, and when disconnected from the hook the table may be elevated by hand power without taxing the operator to move the piston back and forth within the cylinder. It is not absolutely necessary to disconnect the 100 piston but it is desirable to do so when hand operation is continually practised.

Operation by hand is through the medium of a hand lever 36 which is socketed in an off-set 37 on a rock arm 38 pivoted at 39 at 105 one side of saddle 18. Thus, rock arm 38 has an inclined or cam slot 40 within which one end of toggle pin 34 extends and is adapted to ride, and when the lever is drawn forward and downward, the toggles are 110

straightened and the table elevated exactly in the same way as when the piston operates. However, when the lever is forced back to lower the table it is also desirable that it be thrown back far enough to be out of the way in removing or replacing the flask. To that end a curved slot 41 is provided in the rock arm 38 to allow the rock arm to swing rearwardly without actuating the toggle pin 34, and when the rock arm and lever are in this retired position the table is locked against movement. On the other hand when operating with compressed air the lever may be withdrawn from its socket to avoid striking the operator, and locking of the rock-arm is prevented by placing a pin or bolt 37' across the entrance of slot 41, see Figs. 1, 2 and 3.

Squeezing plate 9 is suspended from a screw 42 which is vertically adjustable in the free end of swinging arm 8, and a pair of hand nuts 43 support and lock the screw upon the arm. A pair of collars 44 hold the arm in a swinging and a vertically-adjustable position upon the round post 4, and the arm and squeezing plate may be raised or lowered together to accommodate flasks of different sizes, or the squeezing plate may be adjusted more finely or quickly to the work by manipulating the hand nuts 43. A depending lug 45 on one of the collars 44 is adapted to be engaged by a lateral projection 46 on arm 8 to stop said arm when the squeezing plate is turned and brought over the elevating table. This table is also recessed or open at its center from front to rear, and a stop bar 47 is secured in adjustable position at the rear side of said table by screws or bolts 48 extending through slots 49 and this bar is used to fix the position of the flask in respect to the squeezing plate.

What I claim is:

1. A press of the type described, comprising an elevating table having separate piston and hand lever devices in coacting connection with toggle members to raise and lower said table.

2. In a sand squeezing press, an elevating table, a squeezing plate above said table, toggle members adapted to raise and lower said table, a hand lever adapted to operate said toggle members, and a power piston in detachable connection with said toggle members.

3. A press for squeezing sand in flasks, comprising a vertically-movable table for the flasks, an adjustable squeezing plate above said table, toggle members adapted to raise said table, a piston having a detachable connection with said toggle member, and a hand lever adapted to operate said toggle members independently of said piston.

4. A press for squeezing sand in flasks,

comprising a vertically-movable table for the flask, a swinging arm having a squeezing plate adjustably supported above said table, toggle members and a cam lever adapted to elevate said table, and a cylinder having a piston in detachable link connection with said toggle member and adapted to operate said toggle members independently of said lever.

5. In a press for squeezing sand in flasks, a pair of parallel beams having a post affixed to the upper ends thereof, a cylinder secured in a horizontal position at one side of said beam, a vertically-movable table mounted upon said beams opposite said cylinder, a piston within said cylinder and toggle members for said table in link connection, and a swinging arm mounted upon said post having a squeezing plate mounted for vertical adjustment at its free end and adapted to be turned directly above said table.

6. In a press for squeezing sand in flasks, a pair of spaced upright beams having a horizontal cylinder and a saddle mounted on opposite sides thereof, a table having a supporting stem slidably supported on said saddle, operating connections for said table comprising a piston within said cylinder having a piston rod extending between said beams, and toggle members connected with said saddle and table and said piston rod.

7. In a press for squeezing sand in flasks, an upright support having a cylinder and a vertically-movable table mounted on opposite sides thereof, toggle members adapted to raise said table, a piston within said cylinder having operating connection with said toggle member, and a pivoted hand lever having operating connection with said toggle members adapting movement of said toggle members independently of said piston.

8. A press for squeezing sand in flasks, comprising a vertical support having a vertically-movable table mounted at one side thereof and provided with toggle members having a fulcrum pin extending at one side of said member, a pivoted rock arm having a cam slot in which the said fulcrum pin is adapted to ride, a hand lever for said rock arm, and a squeezing plate adjustably mounted upon said support above said table.

9. A press for squeezing sand in flasks, comprising a table having elevating toggles with a connecting pin, and a lever and rock arm having a cam slot with an extension for said pin to effect either an operating movement of the toggles or to retire the rock arm and lever while the toggles are inactive.

Signed at Cleveland, in the county of Cuyahoga, and State of Ohio, this 7th day of May, 1920.

CHARLES F. SCHULTIS.
